INDUCTION RELAY

John S. Parsons, Swissvale, Pa., assignor to Westinghouse Electric & Manufacturing Company, East Pittsburgh, Pa., a corporation of Pennsylvania

Application November 13, 1934, Serial No. 752,897

9 Claims. (Cl. 175—294)

My invention relates to induction relays and particularly to such relays for use in applications requiring an unusual degree of compactness without sacrifice of torque or accuracy. Although 5 my invention is of general utility in the relay art, it is particularly applicable to power directional network relays and other induction relays which are operated within an outer casing whose dimensions may be dependent upon the dimensions of the relay.

In the smaller sizes of network protectors as used in network distribution systems, the size of a polyphase relay as ordinarily constructed may impose undesirable limitations on the height 15 or depth or the protector casing, particularly where the more compact forms of circuit breaker are used. The usual form of polyphase relay consists of a plurality of discs mounted on a common shaft, with three electromagnetic elements and one or two damping magnets arranged 20 to act on the discs. There are commonly two or three discs used in such a construction.

In accordance with my invention, the disc construction is avoided and the armature element 25 is made in the form of a single conducting drum which is acted upon by all of the electromagnetic elements and one or more damping magnets. However, the drum is not located entirely outside 30 of the electromagnetic elements nor entirely inside, but preferably part of the iron and coils of each element are included within the drum and the remainder arranged outside.

With such an arrangement, I have found that the volume of the relay may be reduced more 35 than 50% and weight to a value approximately 40% less than present designs, while maintaining an equal or higher torque.

It is accordingly an object of my invention to 40 provide a novel induction relay in which the secondary or armature member is cylindrical in form and encloses one polar electromagnetic system, whereas a second polar electromagnetic system is arranged outside of the armature member.

Another object of my invention is to provide 45 a novel induction relay which shall produce a maximum mechanical output for a given relay weight operated at a given efficiency.

Other objects of my invention will become evident 50 from the following detailed description taken in conjunction with the accompanying drawings, in which

Figure 1 is a plan view of a relay embodying 55 my invention with parts broken away and parts shown in section,

Fig. 2 is a sectional view taken on the line II—II of Fig. 1,

Fig. 3 is a view in perspective of the over-voltage adjuster shown in Fig. 1; and,

Fig. 4 is a fragmentary plan view with parts 5 in section of a modified arrangement of electromagnets embodying my invention.

Referring to Figs. 1 and 2, which show an application of my invention to a three-phase network relay, the operating parts of the relay 10 are enclosed in a case comprising a base plate 1 of cast iron or other suitable metal and a glass cover 2 fitted by means of a gasket 2a to the base plate 1 and removably secured thereto by means of posts 3 and thumbscrews 4 in the usual 15 manner.

The base-plate 1 is formed to have a flat portion 1a and a plurality of internally raised bosses 1b for supporting the relay magnetic structure and for providing suitable external space for the 20 attachment of conductors to the relay terminals. The relay is provided with the usual terminals 5 mounted upon the base plate 1 and insulated 25 therefrom by means of suitable insulating spacers 6 and terminal blocks 7 (one of which is shown in the lower left corner of Fig. 2), in the usual manner.

The terminals 5 comprise internally threaded 30 conducting bushings 5a embedded in the terminal block 7 for engagement with externally threaded connecting screws 5b and 5c. The connecting screws 5b pass through insulated terminal assemblies 5d supported by the spacers 6. The spacers 6 are secured to the base plate 1 by means of suitable machine screws 6a.

The relay is provided with three similar electro-magnetic elements 8, two of which are shown 35 in Fig. 1, secured to the base-plate 1 and preferably symmetrically disposed about a common center as indicated. As mentioned above, the induction member of the relay is made in the form 40 of a cylinder or drum 9, subject to the influence of the three elements 8. In accordance with my invention, the magnetic structure comprising the three elements 8 is so arranged that at least one 45 pole of each element, with its associated coil, is mounted within the drum 9, and at least one of the remaining poles of each element with its associated coil is mounted outside of the drum. In the construction shown, each element consists 50 of separate current magnets 10 and potential magnets 11, but, obviously, the invention may be practiced with other arrangements.

The construction of one of the elements 8 is best shown in the upper part of Fig. 1 where 55

parts are broken away and the coils shown in section. The potential magnet **11** is preferably of the iron-clad type and comprises a laminated magnetic core **11a** having a main pole **11b** and a potential coil **11c** mounted thereupon. A lag loop **11d** of copper or other suitable conducting material is mounted in the surface of the core **11a** around the main pole **11b**. The lag loop **11d** is designed to produce a sufficient phase-angle lag in the main pole flux to cause it to be in quadrature to the voltage applied to the coil **11c**, in a manner well understood in the art.

The current magnet **10** comprises a C-shaped magnetic core **10a**, arranged to provide two pole faces **10b** angularly displaced from the main pole **11b** and preferably symmetrically arranged with reference thereto. Suitable coils for obtaining power-directional and phasing operation of the relay are mounted upon the core **10a**. In the embodiment shown, these coils consist of separate current coils **10d** and phasing coils **10e** mounted upon each leg of the C-shaped core, but obviously other well known equivalent arrangements could be used. For example, the phasing coils **10e** could be omitted entirely by arranging the current coils **10d** for phasing operation as well as power-directional operation, in well-known manner.

The drum **9** is secured to a suitable metallic wheel or spider **12**, which in turn is rigidly secured to a main shaft **13**. The main shaft **13** is drilled at either end to receive steel bearing pins **14** which are preferably press-fitted into the holes thus formed.

A frame **15**, preferably of inverted U-shape is secured to the base plate **1** for supporting one end of the main shaft **13**. For this purpose, an adjustable main bearing **16**, having a ring jewel **16a** and a cup jewel **16b**, is centrally mounted in the frame **15**. A similar main bearing **17** is mounted in the base-plate **1** in alignment with the bearing **16**. The bearing arrangement shown is that preferred where the relay is mounted in such position that the main shaft **13** is horizontal. If the relay is operated with its main shaft vertical, the forms of bearings commonly used in vertical shaft relays would, of course, be substituted.

The frame **15** is also provided with an insulated bearing **18** for a contact shaft **20**. The inner end of the contact shaft **20** is mounted in a second insulated bearing **22** supported by means of a metallic member **24** in alignment with the bearing **18**. The member **24** is preferably mounted on the frame **15**.

The moving contact of the relay is preferably in the form of a flat contact spring **25**, rigidly secured to the contact shaft **20** and arranged to make contact with an adjustable tripping contact **27** or an adjustable closing contact **29**.

The contact spring **25** is made somewhat longer than necessary to engage the contacts **27** and **29**, in order to engage a reverse current adjuster **30**. The reverse current adjuster **30** is provided for exerting a biasing torque opposing engagement of the contact spring **25** with the tripping contact **27**, to thereby set an adjustable minimum value to the directional power flow which will effect operation of the relay.

The closing and tripping contacts **29** and **27** respectively and the reverse current adjuster **30** are supported by means of a U-shaped member **31** of insulating material secured to the frame **15**. A spiral spring **33** is secured to the contact shaft **20** and to the frame **15** for biasing the contact spring **25** into engagement with the clos-

ing contact **29**. Movement of the main shaft **13** is transmitted to the contact shaft **20** by means of a pinion **35** press-fitted on the main shaft **13** and arranged to engage a gear wheel **37** secured to the contact shaft **20**.

A permanent damping magnet **38** is secured to the base-plate **1** for damping movements of the induction member **9** in a well-known manner.

An overvoltage adjuster **40** is mounted in any suitable manner for arcuate movement concentric to the main shaft **13**. Although only one overvoltage adjuster **40** is shown in Fig. 1, it will be understood that one is provided for each relay element **8**. The overvoltage adjuster **40** is provided with a flat conducting loop portion **40a** which extends upward between the drum **9** and the potential pole **11b**. The construction of the overvoltage adjuster **40** is best shown in Fig. 3.

A suitable adjusting device **40b** is provided for moving the loop **40a** through a range of positions in front of the potential pole **11b**. The loop **40a** acts to produce a quadrature component of potential pole flux which exerts an adjustable biasing force on the drum **9**, as long as the potential magnet **11c** is energized. The overvoltage adjusters **40** are normally adjusted to produce a total bias slightly greater than that produced by the spring **33** and acting in the opposite direction. In the absence of current flow in the coils **10d** or **10e**, therefore, the spring contact **25** is biased into engagement with the reverse current adjuster **30** when the potential coils **11c** are energized. When the potential coils **11c** are deenergized, the spring **33** maintains the contact spring **25** in engagement with the closing contact **29** as shown.

Inasmuch as the electrical connections of the network relay shown in Figs. 1 and 2 are known in the art and form no part of the present invention, they have not been illustrated. Such connections and the associated auxiliary apparatus are shown and described in the United States patent to Bostwick 1,955,940 for example. However, it will be understood that the relay is used in network protectors associated with polyphase circuits, and causes the network circuit breaker to open in response to directional power flow in excess of a predetermined value in the polyphase circuit and to reclose when the polyphase voltage on the two sides of the circuit breaker bear a predetermined relationship of magnitude and phase position.

Fig. 4 shows an alternative arrangement of the electromagnets used in the practice of my invention. In the Fig. 4 modification, the potential magnets **11** are arranged outside of the drum (not shown in Fig. 4). The current magnets are combined as a unitary structure **41** within the drum. Because of the coil arrangements, it is practical to unite the three magnets within the drum in the Fig. 4 arrangement, whereas in the arrangement of Figs. 1 and 2, the relay may be more conveniently assembled if the potential magnets are kept separate. In the Fig. 4 arrangement, the overvoltage adjusters would, of course, be mounted outside of the drum, rather than inside as in Figs. 1 and 2.

I do not intend that the present invention shall be restricted to the specific structural details, arrangement of parts or circuit connections herein set forth, as various modifications thereof may be effected without departing from the spirit and scope of my invention. I desire, therefore, that only such limitations shall be imposed as are indicated in the appended claims.

I claim as my invention:

1. In an alternating-current relay of the induction type, magnetic structure including a first polar portion and a second polar portion, a first coil means inductively associated with said first polar portion, a second coil means inductively associated with said second polar portion, and an induction member including a conducting portion having the form of a surface of revolution surrounding said first polar portion and said first coil means, said conducting portion being inductively subject to magnetic fields produced by both of said polar portions.
2. In an alternating-current relay of the induction type, a first electromagnet including a core and a coil inductively associated therewith, an induction member including a conducting portion having the form of a surface of revolution surrounding said first electromagnet and subject to the magnetic field produced thereby, and a second electromagnet external to said conducting portion and positioned to magnetically influence said conducting portion, said second electromagnet including a core and a coil inductively associated therewith.
3. In an alternating-current relay of the induction type, magnetic structure including a first polar portion and a second polar portion, a first coil means inductively associated with said first polar portion, a second coil means inductively associated with said second polar portion, and an induction member mounted for rotation about an axis, said member including a conducting portion having the form of a surface of revolution centered on said axis and surrounding said first polar portion and said first coil means, said conducting portion being inductively subject to magnetic fields produced by both of said polar portions, said polar portions being angularly displaced about said axis.
4. In an alternating-current relay of the induction type, a plurality of electromagnetic elements each comprising magnetic structure including a first polar portion and a second polar portion, a first coil means inductively associated with the corresponding first polar portion, and a second coil means inductively associated with the corresponding second polar portion, and an induction member including a conducting portion having the form of a surface of revolution surrounding all of said first polar portions and all of said first coil means, said conducting portion being inductively subject to magnetic fields produced by all of said first polar portions and all of said second polar portions.
5. In an alternating-current relay of the induction type, a plurality of electromagnetic elements each comprising an inner electromagnet and an outer electromagnet, each of said electromagnets including a core and a coil inductively associated therewith, an induction member including a conducting portion having the form of a surface of revolution surrounding all of said inner electromagnets and subject to the magnetic fields produced thereby, said outer electromagnets being positioned to inductively influence said conducting portion.
6. In an alternating-current relay of the induction type, a plurality of symmetrically disposed electromagnetic elements each comprising an inner electromagnet and an outer electromagnet, each of said electromagnets including a core and a coil inductively associated therewith, an induction member including a conducting cylindrical portion surrounding all of said inner electromagnets and subject to the magnetic fields produced thereby, said outer electromagnets being positioned to inductively influence said conducting portion.
7. In an induction relay, an induction member including a conducting portion of substantially cylindrical form, electromagnetic energizing means including a polar portion arranged to inductively influence said conducting portion, a shading device having an electrically closed shading circuit, and adjustable mounting means for said shading device arranged to permit arcuate movement of said shading circuit between said polar portion and said conducting portion along a path substantially concentric to the axis of said conducting portion.
8. In a network relay of the induction type, electromagnetic energizing means including a first polar portion and a second polar portion, an induction member including a conducting portion having the form of a surface of revolution surrounding said first polar portion, said conducting portion being inductively subject to magnetic fields produced by both of said portions, a shading device having an electrically closed shading circuit, and adjustable mounting means for said shading device arranged to permit arcuate movement of said shading circuit between one of said polar portions and said conducting portion along a path substantially concentric to the axis of said conducting portion.
9. In a network relay having a potential pole, an overvoltage adjuster comprising a conducting loop portion inductively associated with said pole and an arcuate rack portion concentric with a point fixed with reference to said pole, an adjusting pinion in mesh with said rack, and means for confining movement of said adjuster to an arcuate path concentric with said point.

JOHN S. PARSONS.
